(57) **CLAIM**

We claim the ornamental design for a styling iron, as shown and described.

DESCRIPTION

FIG. 1 is a perspective view of the styling iron;
FIG. 2 is a right view of the styling iron;
FIG. 3 is a left view of the styling iron;
FIG. 4 is a top view of the styling iron;
FIG. 5 is a bottom view of the styling iron;
FIG. 6 is a front view of the styling iron; and,
FIG. 7 is a rear view of the styling iron.
The broken lines illustrate portions of the styling iron and
form no part of the claimed design.
